UNITED STATES PATENT OFFICE.

JAMES FRANK PARHAM, OF NASHVILLE, TENNESSEE.

INK-FOUNTAIN FOR PRINTING-PRESSES.

1,334,469.

Specification of Letters Patent. Patented Mar. 23, 1920.

Application filed March 3, 1919, Serial No. 280,440. Renewed February 10, 1920. Serial No. 357,747.

To all whom it may concern:

Be it known that I, JAMES FRANK PARHAM, a citizen of the United States, and a resident of Nashville, in the county of Davidson and State of Tennessee, have invented certain new and useful Improvements in Ink-Fountains for Printing-Presses, of which the following is a specification.

My present invention relates generally to ink fountains, and more particularly to ink fountains for job printing presses, my object being the provision of an inking attachment by means of which the actual printing may be improved and much time saved in operation.

A further and more specific object is the provision of an ink fountain in which the ink receptacle may be readily removed for cleaning and repair and a further object is the provision of means whereby the ink receptacle may be locked in positive adjustment with respect to the inking roller so as to maintain an even color in the printing throughout an entire job.

A still further object is the provision of an arrangement which may be secured in inoperative position when the fountain is not in use and a construction by means of which streaking of forms may be readily overcome and entirely eliminated.

Other objects, relating for the most part to the details of construction, will more plainly appear in the following description, reference being made to the accompanying drawings, forming a part of this specification, and in which:

Figure 1 is a side elevation of my improved attachment,

Fig. 2 is a top plan view thereof,

Fig. 3 is an end view, looking at the distributing roller and its frame,

Fig. 4 is a top plan, side and end view of the ink receptacle, and

Fig. 5 is a detail plan view of the adjusting screw removed.

Referring now to these figures, my improved attachment is connected to the frame of a platen printing press through the use of a bracket 14, one end 30 of which, as seen in Fig. 2, is slotted for adjustable engagement by a connecting bolt which secures it to the machine, and the other of which is connected by a bolt 15 to the base of the fountain frame 1, the rear wall of which has a bearing 3 for the adjusting screw 31, the latter being engaged by a lock nut and handle 4 the turn-

ing of which against the rear end of the frame 1 securely locks the adjusting screw in adjusted position.

The forward portion of the frame 1 has 60 bearings for the shaft 13 of the inking roller 10, upon which is secured a ratchet wheel 9, and to one end of which is affixed a screw 12 on which the forward end of a ratchet lever 28 is journaled, this lever carrying a dog 5 65 in engagement with the ratchet base of the wheel 9.

The ends of the shaft 13 also extend through the side portions of a frame 6, one side portion of which is extended rearwardly 70 as best seen in Fig. 2 and secured by screws 11 to the ratchet lever 28 so that the entire frame 6 tilts on the shaft 13 in operation and thus the ratchet wheel is given a step-by-step rotative movement, turning the inking roller 10.

Within the sides of the frame 1 and seated upon the base thereof is the fountain or ink receptacle 2, the forward portion of the sides of which have concave recesses 37 which abut 80 the annular shoulders 23 at the opposite ends of the inking roller 10. This fountain or ink receptacle 2 also has its base forwardly and downwardly inclined and terminating in a knife edge 38 adjacent to the 85 periphery of the inking roller 10, and is provided with a rear wall 32 having a vertical slot 36 which receives the forward reduced extension 34 of the adjusting screw 31, the threaded portion 33 of which extends 90 through the bearing 3. This adjusting screw 31 has at its inner end a head 35 and thus with the reduced portion 34 thereof in the slot 36 of the rear wall 32 of the fountain, when the latter is disposed in the operative 95 position shown in Figs. 1 and 2, rotation of the adjusting screw serves to shift the ink receptacle or fountain forwardly and rearwardly dependent upon the direction of such rotation.

The side walls of the frame 1 have clips 27 secured thereto by screws as clearly seen in Figs. 1 and 2 and by virtue of the particular connection of the fountain with the adjusting screw, as well as the character of the 105 clips 27, it is simply necessary to loosen these clips in order to withdraw the fountain or ink receptacle for cleaning.

Forwardly beyond the inking roller 10, the frame 6 which, as before stated, is secured to the ratchet lever 28 and tilts upon the shaft 13 of the inking roller, is provided

402

5

with a cross bar 29 and forward extensions, to the latter of which a depending frame of inverted U-shape is pivoted by pivot screws 18 and normally held in vertical position by means of a spring 21. This frame 17 supports at its lower portion a journal or shaft 26 of a distributing roller 22 which, upon rocking movement of the frame 17 upon the pivot screws 18, comes into engagement with the inking roller 10 as presently described. The frame 17 may normally be held in the vertical position shown in Fig. 1 and secured against movement by a clamp screw 19, when the fountain is not in use, and to the lower portion of the said frame 17 and extending rearwardly and laterally therefrom, is an angular bracket 23, connected by screws 25 extending through its slots 24 and provided with an angular extremity 40 into engagement with which the form roller saddle of the printing press comes during the operation of the latter, so as to shift the frame 17 and move the distributing roller 22 into engagement with the inking roller 10. The spring 21 is secured to the frame 6 at its upper end by a screw 20 and engages the bracket 23 at its lower end so that after each movement of the distributing roller 22 upwardly and rearwardly against the inking roller 10, the spring 21 will draw the distributing roller frame 17 downwardly again upon the next movement of the form rollers over the impression form.

The inking device is of course mounted adjacent to the inking disk of the press as usual, so that in the downward movement of the distributing roller 22 to the position shown in Fig. 1, it comes into engagement with the surface of the said disk so as to transfer thereto the ink it has received from the surface of the inking roller 10.

To the rear end of the ratchet lever 28, a connecting rod or arm 8 is loosely connected by a pivot bolt 7, the rod or arm 8 leading from a suitable moving part of the press as usual, so that during the operation of the press the inking roller 10 is, through the connections above stated, given a step-by-step rotation. It is obvious that in addition to the advantages above set forth to the ready removal of the ink receptacle or fountain 2, my improved construction provides for readily locking the ink receptacle in adjusted relation with respect to the inking roller 10 so as to avoid all danger of displacement, and in this way assure a uniform

color throughout the printing operation, and it is further obvious that my improved construction has the advantages of simplicity, reduced cost and increased strength over constructions for a similar purpose now in use.

By removing the spring and the part 23, and by tightening the screws 18 and 19, the distributing roller may be used with an up and down movement, the form roller receiving the ink from the fountain roller 10 and placing the ink on the disk where it is distributed evenly by the distributing roller.

I claim:

1. An inking attachment of the character described including a main frame, a shaft journaled in the said frame at one end, an inking roller on the said shaft, a ratchet wheel also secured upon the shaft, a tiltable frame journaled on the ends of the shaft and having actuating connections, and a portion projecting beyond the inking roller, a dog moving with the said tiltable frame and engaging the ratchet wheel, a spring controlled frame pivotally connected to and depending from the projecting portion of said tiltable frame, a distributing roller journaled in the latter frame, and a bracket secured to the said distributing roller frame and projecting laterally therefrom, for the purpose described.

2. An inking attachment of the character described including a main frame having side walls provided with bearings at one end, a shaft journaled in the said bearings, an inking roller on the said shaft between the side walls of the frame, a ratchet wheel also secured upon the shaft at one side of the frame, a tiltable frame journaled intermediate the ends of its side portions, upon the ends of the said shaft, said tiltable frame having actuating connection and a portion projecting beyond the inking roller, a dog moving with the tiltable frame and engaging the said ratchet wheel, a spring controlled frame pivotally connected to and depending from the projecting portion of said tiltable frame, a distributing roller journaled in the latter frame, and a bracket secured to the said distributing roller frame and projecting laterally therefrom, for the purpose described.

JAMES FRANK PARHAM.
